UNITED STATES PATENT OFFICE.

JAMES T. LYKENS, OF HUNTINGTON, WEST VIRGINIA, ASSIGNOR OF ONE-HALF TO
LEMUEL R. VIA, OF HUNTINGTON, WEST VIRGINIA.

EXPLOSIVE-ENGINE IGNITER.

Application filed May 10, 1923. Serial No. 638,020.

To all whom it may concern:

Be it known that I, JAMES T. LYKENS, a citizen of the United States, residing at Huntington, in the county of Cabell and State of West Virginia, have invented certain new and useful Improvements in Explosive-Engine Igniters; and I do hereby declare the following to be a full, clear, and exact description of the invention, such as will enable others skilled in the art to which it appertains to make and use the same.

The invention relates to ignition means for explosive engines and has for its object to provide an igniter which is adapted to act jointly with the ordinary spark plug or independently thereof to prevent misfiring and to obviate flooding of the cylinder and to insure a dry combustion at all times with the result that the engine is rendered smooth running and its power materially increased.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the nature of the invention.

Referring to the accompanying drawing forming a part of the application, the same is a sectional view illustrative of the invention.

The numeral 1 designates the cylinder of an internal combustion engine and 2 the piston operable therein. These parts may be of any design and are illustrated to demonstrate the application of the invention. The cylinder 1 is provided with the usual threaded opening 3 for reception of the spark plug which, in the present instance, is replaced by the igniter which, as shown, comprises a shell 4 of approximately L-form, one branch being externally screw threaded to enter the opening 3 and the other branch being enlarged and internally screw threaded to receive a spark plug 5 which may be of any make or design commonly provided for internal combustion engines. A stem 6 passes

centrally through the vertical branch of the shell 4 and its inner or lower end is enlarged, as indicated at 7. The stem 6 projects beyond the horizontal branch of the shell and is threaded therein, as indicated at 8, and the projecting end is provided with a thumb button 9, whereby the stem may be rotated to adjust the relative position of the enlarged end 7, whereby it may project more or less from the inner end of the shell, as required. The stem 6 constitutes the igniter and consists of metal which is highly susceptible to changes in temperature so as to rapidly absorb heat and quickly give off the heat thus absorbed.

It is the intention to use the igniter in conjunction with the spark plug and in the event of the plug failing to properly function, the igniter will operate to explode the charge and thereby prevent misfire. After the engine has been started and several explosions take place, the ignition member 6 becomes heated to such an extent as to explode the charge and the successive explosions maintain the igniter at the proper temperature to explode the charges, even though the spark plug should fail to function.

What is claimed is:

1. Ignition means for explosive engines, the same comprising a shell adapted to be coupled to the cylinder of an engine and adapted to receive an ordinary spark plug, and an ignition member within the shell and adapted to be heated by the explosion of the gaseous mixture, whereby to ignite and explode the successive charge.

2. Ignition means for explosive engines, the same comprising a shell adapted to be coupled to the cylinder of an engine and adapted to receive an ordinary spark plug, and an ignition member within the shell and having its inner end enlarged.

3. Ignition means for explosive engines, the same comprising a shell adapted to be coupled to the cylinder of an engine and adapted to receive an ordinary spark plug, and an ignition member within the shell and having adjustable connection therewith and having its inner end enlarged.

4. Ignition means for an explosive engine comprising a shell of approximately

L-form, one branch being externally screw threaded to make connection with the engine and the other branch being internally screw threaded to receive a spark plug, and
5 an ignition member within the externally screw threaded branch and projecting beyond the internally screw threaded branch and having screw thread connection therewith

and provided at its outer end with a thumb button and having its inner end enlarged. 10

In testimony whereof I affix my signature in presence of two witnesses.

JAMES T. LYKENS.
